UNITED STATES PATENT OFFICE.

CHARLES B. BOSWORTH, OF EVERETT, ASSIGNOR TO THE CROSBY STEAM GAGE AND VALVE COMPANY, OF BOSTON, MASSACHUSETTS.

DEVICE FOR REGULATING FEED-WATER.

SPECIFICATION forming part of Letters Patent No. 441,741, dated December 2, 1890.

Application filed November 1, 1890. Serial No. 370,005. (No model.)

To all whom it may concern:

Be it known that I, CHARLES B. BOSWORTH, a citizen of the United States, residing at Everett, in the county of Middlesex, and State of Massachusetts, have invented certain new and useful Improvements in a Device for Regulating Feed-Water; and I do hereby declare the following to be a full, clear, and exact description of the invention, such as will enable others skilled in the art to which it appertains to make and use the same.

Figure 1 is a side elevation in which the several devices employed are shown in combination, viz: the steam-boiler A, the steam-feed-pump B, with its throttle-valve C, the air-pump D, which is mounted on the feed-pump B and receives its motion therefrom, the air-pressure governor E, and the thermostat E'. Fig. 2 is a top view of the air-pressure governor E, and Fig. 3 is a vertical section through the axis of the governor, on the line $x-x$, Fig. 2, and Fig. 4 is a similar vertical section through the axis of the instrument on the line $a-a$, Fig. 2, showing how the air-pressure is introduced into the piston-chamber of the governor. Fig. 5 is a modified shape of the thermostatic tube.

Secured to the boiler A is the usual water column M, the sight-glass of which is removed so as to clearly show the thermostat. Attached to this water column is the thermostat E', an enlarged view of which, though of somewhat changed shape, is shown in Fig. 5. This consists of an expansion-tube e, having a pipe e^5 for connection at the top with the water column and the pipe e^9 at the bottom for a similar connection.

The form shown at Fig. 5 presents an arrangement of parts in which e is the expansion-tube, having a pipe-connection at either end, the upper one G leading to the steam-space and the lower one H to the water-space of a steam-boiler, these pipes being so attached that the proper water-level of the boiler will correspond to the longitudinal axis of the tube e, the water rising and falling in tube e conformably to the rise and fall of the water in the boiler, the water entering through pipe H and the steam through pipe G. The right-hand branch of the piece I is closed

by a plug having a forked standard J projecting outward from it, providing a carrying-pivot for the lever p, the lower end of which is connected by the tension-rod t to a fixed collar f at the opposite end of the tube e. The upper end of the lever carries a set-screw to regulate the operation of the valve j under the action of the expansion-tube.

In the form at Fig. 5 the spring e^4 (shown in Fig. 1) is omitted, the strain on lever p and tension-rod t being governed by a set-screw q.

In Fig. 1 is shown the connection of the thermostat with the pump and throttle-valve governor. The pipe n leads from the valve j by the pipes b' to the air-pump D and to the air-pressure governor E.

As shown in Figs. 2, 3, and 4, the upper part of the air-pressure governor E is divided by a horizontal partition a' into two chambers, the lower one d' being occupied by a cylindrical piston e', and the upper one by the annular piston f'. These two pistons are connected together by the central stem g' and yoke h'. The upper cylinder contains oil and acts as a dash-pot to prevent a too rapid movement of the working parts when called into action. The space between the under side of partition a' and the top of the cylindrical piston e' contains compressed air, supplied by the air-pump D, which is mounted upon the steam-pump B, and from it receives its motion. The compressed air is conveyed to cylinder d' by the pipe b' b' b' b', and by a branch of this pipe (shown at n n n) it is conveyed to the air-relief valve j of the thermostat.

The air-pressure governor E is mounted upon the top of the throttle-valve casing of the steam-pump and governs the opening and closing of that valve, which is connected with the piston e' by a screw-ended rod, which is inclosed in a strong spiral spring i', the tension of which may be modified by means of the screw-nut j'. At its lower end the spiral spring rests on the top of the packing-box of the throttle-valve spindle at k'. It will be understood that the downward pressure on the piston of cylinder d' and the upward force exerted by the spiral spring i' are in direct opposition. The pipe K K' conveys

steam from the boiler to the steam-pump, and the pipe l conveys the feed-water from the steam-pump to the boiler. The set-screw l' is to modify the passage of the oil by the piston f' , and the petcock c' on the pipe b' is to modify the air-pressure within the air-pipes as may be desired.

- The operation of the combined devices herein described is as follows: The steam-pump B having been put in motion, the air-pump D , connected therewith, begins to force air into the pipes b' and into the chamber d' above the piston e' . As the air-pressure accumulates in the chamber d' the piston e' is pressed toward against the expansive force of the spiral spring i' , and the throttle-valve O of the steam-pump being thereby partly closed, the movement of the steam and air-pump pistons is correspondingly retarded. If the steam-pump is working too slow, the water-line of the boiler will be lowered, so that the water in the expansion-tube e will run into the boiler and be replaced by steam, which will expand the tube longitudinally, causing an outward movement of the upper end of the lever p , which will open the air-relief valve j , letting air escape, when, under the resilient action of the spiral spring i' , the piston e' will rise, opening the throttle-valve of the steam-pump and accelerating its motion.
- 15
- 20
- 25
- 30

If the steam-pump is working too fast, the water-line of the boiler will rise, so that steam contained in the expansion-tube e will be expelled therefrom by the incoming water, which will be cooled by radiation from the metal of the tube and will contract longitudinally, permitting the spring c^4 to hold the air-relief valve j to its seat, preventing the escape of air from the pipes b' and n and chamber d' of the governor. The air accumulation in chamber d' will now press down the piston e' against the resilient force of the spiral spring i' , partly closing the throttle-valve of the steam-pump and retarding its motion.

Having thus described my invention, what I claim is—

As an improvement in boiler-feeders, an expansion-tube having at each end a pipe for communicating with the boiler, an air-valve and a lever attached to such valve and to the tube, and means for connecting said valve with a throttle-valve governor, as set forth.

In testimony whereof I affix my signature in presence of two witnesses.

CHARLES B. BOSWORTH.
